[57] **CLAIM**

The ornamental design for a front panel for all-purpose electric fence insulator, substantially as shown and described.

DESCRIPTION

FIG. 1 is a perspective view of the front panel of an all-purpose electric fence insulator embodying our new design, the broken lines denoting environmental structure for holding the electric fence wire in actual use; FIG. 2 is a front elevational view thereof; FIG. 3 is a top plan view thereof; FIG. 4 is a bottom plan view thereof, and FIG. 5 is a side elevational view taken from the left in FIG. 2.
